UNITED STATES PATENT OFFICE.

JOHN H. GAVIN, OF CHICAGO, ILLINOIS, ASSIGNOR TO THE L. WOLFF MANUFACTURING COMPANY, OF SAME PLACE.

DESIGN FOR A WASHBOWL AND SLAB.

SPECIFICATION forming part of Design No. 23,806, dated November 13, 1894.

Application filed September 4, 1894. Serial No. 522,140. Term of patent 14 years.

To all whom it may concern:

Be it known that I, JOHN H. GAVIN, a citizen of the United States, residing at Chicago, in the county of Cook and State of Illinois, have invented and produced a new and original Design for a Washbowl and Slab, of which the following is a specification, reference being had to the accompanying drawing, forming a part thereof.

The drawing shows a perspective view of a wash bowl and slab embodying my design.

The leading feature of my design consists in the general shape and outline of my wash bowl and slab as a whole, in connection with the decoration upon the exterior of the bowl portion proper thereof, as illustrated in the drawing.

In the drawing A is the bowl.

B is the horizontal slab.

C is the vertical back slab, and D D are the two side slabs or walls uniting the back slab, the horizontal slab and the bowl.

The horizontal slab B is made in an annular or rim like form b at the front side of the bowl and thus given the appearance of a rounded rim for the bowl.

The two side slabs D D each have an ogee curved outline d d at their upper vertical edges, and these upper ogee curved edges d d of the sides D D are given rounded edges or rims d' d' so that these rounded and ogee out-

lined edges d' d' of the sides D D unite with and form a continuation of the horizontal annular rim portion b of the slab B as shown in the drawing.

The outline of the back C comprises two ogee curves c c and a common or union curve c' joined to the curve c c by angular offsets c². The vertical face of the back C is furnished with lines c³ c³ c³ parallel to the curved and 40 angular lines c c² c' c² c as indicated in the drawing so as to form a belt c⁴ conforming to or constituting a continuation of the semi annular rim b, the rounded edges d' d' of the sides D D as the ogee curves unite with the 45 ogee curves d d at the angles between the back C and the sides D D. The sides D also have an ogee curve d² projecting downward from the rim b.

The bowl A has the curved, fluted or scalloped decoration a a, the points of which terminate at the center or outlet of the bowl A, and also the fillet or skirt like decoration a' comprising the members a² a³ and a⁴, as clearly shown in the drawing.

I claim—

The design for a wash bowl and slab herein shown and described.

JOHN H. GAVIN.
